UNITED STATES PATENT OFFICE

171,585

LOUNGE CHAIR

Nathan N. Elman, Chicago, Ill.

Application June 22, 1953, Serial No. 25,590

Term of patent 14 years

(Cl. D15—1)

To all whom it may concern:

Be it known that I, Nathan N. Elman, a citizen of the United States, residing at Chicago, in the county of Cook and State of Illinois, have invented a new, original, and ornamental Design for a Lounge Chair, of which the following is a specification, reference being had to the accompanying drawings forming a part thereof.

Fig. 1 is a perspective view of a lounge chair illustrated in upright position, showing my new design.

Fig. 2 is a front elevational view.

Fig. 3 is a top plan view.

Fig. 4 is a side elevational view.

Fig. 5 is similar to Fig. 4 but showing the lounge chair in a reclined position.

The characteristic features of the design are represented in full lines on the drawings.

I claim:

The ornamental design for a lounge chair, substantially as shown and described.

NATHAN N. ELMAN.
